UNITED STATES PATENT OFFICE

160,107

PORTABLE-TYPEWRITER DESK

David A. Moffitt, Duluth, Minn.

Application July 20, 1949, Serial No. 4,006

Term of patent 14 years

(Cl. D33—7)

To all whom it may concern:

Be it known that I, David A. Moffitt, a citizen of the United States, residing at Duluth, in the county of St. Louis and State of Minnesota, have invented a new, original, and ornamental Design for a Portable-Typewriter Desk, of which the following is a specification, reference being had to the accompanying drawing, forming part thereof.

The figure is a perspective view of a portable-typewriter desk, showing my new design.

I claim:

The ornamental design for a portable-typewriter desk, as shown.

DAVID A. MOFFITT.
